W. A. SMITH

BLOWING DEVICE

Filed August 7, 1925

UNITED STATES PATENT OFFICE.

WILLIAM A. SMITH, OF ATHENS, PENNSYLVANIA, ASSIGNOR TO INGERSOLL-RAND COMPANY, OF JERSEY CITY, NEW JERSEY, A CORPORATION OF NEW JERSEY.

BLOWING DEVICE.

Application filed August 7, 1925. Serial No. 48,713.

This invention relates to rock drills, but more particularly to a blowing device for fluid actuated rock drills of the hammer type.

5 The objects of the invention are to selectively admit an uninterrupted supply of pressure fluid under full line pressure to the drill steel for cleansing the drilled hole and to hold the valve and the piston immovable 10 while such pressure fluid is passing through the drill steel.

Other objects will appear hereinafter.

The invention consists of the combinations of elements, features of construction, 15 and arrangement of parts having the general mode of operation, substantially as herein-after described and more particularly pointed out in the appended claims and illustrated in the accompanying drawings, in 20 which—

Figure 1 is a longitudinal diagrammatic view in section of so much of a rock drill as will serve to illustrate the invention,

25 Figure 2 is a view similar to Figure 1 showing the reciprocating parts in another position, and

Figure 3 is a view similar to Figures 1 and 2 showing the manner in which pressure fluid is admitted to the drill steel.

30 Referring to the drawings, the invention is shown embodied in a drill having a cylinder A provided with a reciprocatory hammer piston B. A front head C is arranged at the front end of the cylinder A and is centralized with respect thereto by a front cylinder washer D. The cylinder A and the front head C are preferably held in operative position by the usual side bolts (not shown).

40 Disposed within the front head C is a rotatable chuck E having ribs F which cooperate with flutes G formed on an extension H of the piston B to prevent relative rotation between said piston and the chuck 45 E. The front end of the chuck E is bored as at J to receive a drill steel K and to hold said drill steel against rotation with respect thereto.

50 In order to impart rotary movement to the piston B and consequently the drill steel K for keeping the drill steel free within the drill hole, a rifle bar L engages the piston B in the usual manner and may be held in any convenient manner against rotation 55 while the piston is traveling in one direc-

tion and to permit rotation of the rifle bar with the piston during the opposite stroke of the piston. The rifle bar L in this instance is adapted to project through a back cylinder washer O fixed in the rear end of the cylinder A to form a seal for said cylinder, the entire construction not being shown. A valve chest P is in this instance arranged longitudinally of the cylinder A and has a valve chamber Q in which chamber is arranged a spool type distributing valve R. The type of valve here illustrated is like that covered in the copending application of W. A. Smith Serial No. 23,181, filed, April 15, 1925, although any suitable valve in which 60 kicker ports are employed for actuating the valve may be used. The valve shown has a central head S which controls a central inlet port T and has end heads U and V for controlling the main exhaust ports W and X 65 respectively formed on opposite sides of the inlet port T. The ends of the chamber Q are closed by bushings Y which also serve as stops for limiting the travel of the valve R. Motive fluid for actuating the piston is 70 supplied to the rear and front ends of the cylinder through supply passages Z and b respectively communicating with the valve chamber Q on opposite sides of the central inlet port T. 75

Usually in drills employing valves of the type indicated in the drawings, kicker ports are used for controlling the action of the valve. Such kicker ports may be crossed as in the present instance in which a kicker 80 port c leading from a point rearward of the center of the cylinder A communicates with the front end of the valve chamber Q to admit pressure fluid to said front end for throwing the valve rearwardly. A second 85 kicker port or passage d communicating with the cylinder A at a point forwardly of its center extends to a bore e formed through the valve chest P between the chamber Q and the cylinder A. Disposed within the bore e is a hollow rotatable plug f having an ablong port g adapted to constantly 90 register with the passage d. A port h is formed near the rearward end of the hollow plug to register with a passage j leading 95 from the bore e to the rearward end of the valve chamber Q. 100

Means are also provided for establishing communication between the hollow plug f and the front end of the valve chamber Q. 110

and to that end a port *k* is formed in the front end of the hollow plug *f* to register with a passage *o* in the valve chest communicating at one end with the front end 5 of the chamber *Q*. A handle or lever *p* is secured to one end of the hollow plug *f* for rotating said plug and, as in the present instance, may prevent longitudinal movement of the plug in one direction. A nut *q* 10 screwed on the opposite end of the plug *f* prevents endwise movement of said plug in the other direction.

In the operation of the device with the parts in the positions indicated in Figure 1, 15 pressure fluid for reciprocating the piston *B* is distributed to the opposite ends of the cylinder in the usual manner by the valve *R*. During the normal operation of the drill, some leakage may occur between the 20 piston extension *H* and the adjacent parts to the drill steel. Such leakage, however, is insufficient to properly cleanse the drill hole. If, after a certain period of drilling, it is desired to more thoroughly cleanse the 25 drill hole, the plug *f* may be rotated a quarter turn from its normal position as shown in Figures 1 and 2 to that shown in Figure 3. In this position, the port *h* is moved out of registration with the passage *j* at the 30 rearward end of the valve chamber *Q* and at the same time the port *k* is moved into registration with the passage *o* leading to the front end of the valve chamber *Q*. With the plug in this position, a portion of the 35 pressure fluid admitted through the supply passage *b* to the front end of the cylinder *A* will pass through the passage *d* and the port *g*, thence through the hollow plug *f* and through the port *k* and the passage *o* into the front end of the chamber *Q* and hold 40 the valve against the rearward bushing *Y*. By thus holding the valve rearwardly and immovable the front supply port *b* will be in constant communication with the inlet port 45 *T* to admit pressure fluid to the front end of the cylinder. In this way the piston *B* is moved to the rearward limiting position shown in Figure 3. With the piston in this position the flutes *G* are partly withdrawn 50 from the ribs *F* and pressure fluid under full line pressure passes through the front cylinder washer *D* and the chuck *E* into the drill steel *K* to blow the cuttings from the drill hole. After the drill hole has been 55 thoroughly cleansed, the hollow plug *f* may again be rotated to the position shown in Figures 1 and 2 and the valve and the piston will again function in their normal manner.

60 I claim:

1. In a blowing device for a fluid actuated rock drill, the combination of a cylinder with a front head, a hammer piston in the cylinder, a fluted forward extension on said 65 hammer piston, a drill steel supported in

the front head to receive the blows of said fluted extension, a valve chest on the cylinder having a chamber, supply passages and kicker ports leading from the chamber to the cylinder, a distributing valve in said valve chest, and means rotatable in the valve chest for controlling one of the kicker ports to admit pressure fluid from the cylinder to the chamber, the pressure fluid thus admitted acting to hold the valve immovable in the chamber to permit a continuous supply of pressure fluid from the chamber to one end of the cylinder and along the fluted extension to the drill steel. 75

2. In a blowing device for a fluid actuated 80 rock drill, the combination of a cylinder with a front head, a hammer piston in the cylinder, a fluted extension on said hammer piston, a drill steel supported in the front head to receive the blows of said fluted extension, a valve chest on the cylinder having a chamber, supply passages and kicker ports leading from the chamber to the cylinder, a distributing valve in said chamber, and manually controlled rotary means in 85 the valve chest forming part of one kicker port for admitting pressure fluid from the cylinder to the chamber, the pressure fluid thus admitted acting to hold the valve immovable in one end of the chamber to permit an uninterrupted supply of pressure fluid from the chamber to one end of the cylinder and from the cylinder along the fluted extension to the drill steel. 95

3. In a blowing device for a fluid actuated 100 rock drill, the combination of a cylinder with a front head, a hammer piston in the cylinder, a fluted forward extension on said hammer piston and extending into the front head, a drill steel supported in the front head to receive the blows of said fluted extension, a valve chest on the cylinder having a chamber, supply passages and kicker ports leading from the chamber to the cylinder, a distributing valve in said chamber, and a 105 hollow rotatable plug in the valve chest forming part of one kicker port for admitting pressure fluid from the cylinder to one end of the chamber, the pressure fluid thus admitted acting to hold the valve immovable in the opposite end of the chamber to admit an uninterrupted supply of pressure fluid from the chamber to the cylinder for withdrawing the fluted extension partly from the front head and to permit pressure fluid 110 to flow from the cylinder to the drill steel. 115

4. In a blowing device for a fluid actuated rock drill, the combination of a cylinder with a front head, a hammer piston in the cylinder, a fluted forward extension on the hammer piston and reciprocable in the front head, a drill steel supported in the front head to receive the blows of said fluted extension, a valve chest on the cylinder having a chamber, supply passages and 120

kicker ports leading from the chamber to the cylinder, a valve in said chamber, and a hollow plug in the valve chest forming part of one kicker port when in one position and adapted to be rotated to another position for admitting pressure fluid from the cylinder to the front end of the chamber to hold the valve immovable in the rearward end of said chamber in which position of the valve an uninterrupted supply of pressure fluid is admitted from the chamber to the cylinder for withdrawing the fluted extension partly into the cylinder and for permitting an uninterrupted flow of pressure fluid along said fluted extension to the drill steel.

5. In a blowing device for a fluid actuated rock drill, the combination of a cylinder with a front head, a hammer piston in the cylinder, a fluted forward extension on the hammer piston and reciprocable in the front head, a drill steel supported in the front head to receive the blows of said fluted extension, a valve chest on the cylinder hav-

ing a chamber, supply passages and crossed front and rear kicker ports leading from the chamber to the cylinder, a distributing valve in the chamber, a bore between the chamber and the cylinder, a passage leading from the bore to the front end of the chamber, and a hollow plug in the bore forming part of one kicker port when in one position and adapted to be rotated to another position to register with said passage for admitting pressure fluid from the cylinder to the front end of the valve to hold said valve immovable in the rearward end of the chamber, in which position of the valve pressure fluid may pass from the chamber to the front end of the cylinder for holding the piston in the rearward end of the cylinder to permit the passage of pressure fluid through the flutes in the extension and through the drill steel.

10 In testimony whereof I have signed this 45 specification.

WILLIAM A. SMITH.
